F. R. COATS.
DETACHABLE REFLECTOR FOR VEHICLE LAMPS.
APPLICATION FILED MAY 25, 1918.

1,314,047.

Patented Aug. 26, 1919.

UNITED STATES PATENT OFFICE.

FRED R. COATS, OF SPRINGFIELD, ILLINOIS.

DETACHABLE REFLECTOR FOR VEHICLE-LAMPS.

1,314,047.

Specification of Letters Patent. Patented Aug. 26, 1919.

Application filed May 25, 1918. Serial No. 236,500.

To all whom it may concern:

Be it known that I, FRED R. COATS, a citizen of the United States, residing at Springfield, in the county of Sangamon and State of Illinois, have invented a new and useful Detachable Reflector for Vehicle-Lamps, of which the following is a specification.

The invention relates to reflectors such as 10 are used on automobile lamps, or other similar lamps, to reflect downward the greater part of the light to illuminate the road in front of the vehicle and spread the light on each side of the road so that the driver may 15 have a clear view of the way he is traveling, while part of the lamp is covered so that the glare of the direct light will not dazzle persons in front of the lamps.

The purposes of the invention are, to provide 20 a reflector of a form especially suitable for the use described and to provide simple and effective adjustable connecting devices adapted for use with lamps of different sizes and so constructed and arranged that the reflector may be easily and quickly connected with or detached from lamps of different sizes.

The invention is illustrated in the annexed drawing, to which reference is hereby made, 30 and will now be described and the new and useful features thereof will be recited in the claims.

Figure 1 is a front elevation of a lamp equipped with a detachable reflector embodying the invention.

Fig. 2— is a vertical section on the line X. X. of Fig. 1.

Fig. 3— is a horizontal section on the line Y. Y. of Fig. 1, looking upward.

Fig. 4— is a partial vertical section on the line Z. Z. of Fig. 3.

Fig. 5— is a fragmentary sectional diagram illustrating a visor-shape reflector and connections of modified construction; and

Fig. 6— is a reduced sectional diagram showing the permanent reflector of the lamp; the visor-shape detachable reflector; and a hemispherical concavo-convex shield in correlation to each other.

The same reference numerals designate the same parts in the different views.

The lamp body 1, the stationary reflector 2 and the light 3, may be of any standard or approved construction. A cap ring 4, preferably of the form shown, keeps the glass 5 in place in front of the lamp.

The detachable reflector is preferably of thin sheet metal, for the sake of lightness and flexibility and comprises a visor-shape body 6 having a polished inner reflecting 60 surface, an approximately circular integral corrugated part 7 adapted to fit around the greater part of the circumference of the cap-ring 4; and strap-members 8 and 12. The strap-member 8 has an ear 9 having a hole 65 10. The strap-member 12 has a series of holes 13. The hasp 14 is conformed to the outer surface of the strap-member 12 and has at one end a hook 15 adapted to enter the holes 13 in the strap-member 12, and has 70 75 at its other end an ear 16 having a hole 17 in line with the hole 10 of the ear 9. A screw 18 extends through the holes 17 and 10 and engages in a stationary nut 19 to connect the hasp 14 with the strap-member 8. By changing the hook 15 from one hole 13 to another, the strap, as a whole, may be lengthened or shortened, as the case may be, to conform to lamps of different circumferences.

I have shown and described, and prefer to use, a detachable reflector having an adjusting strap comprising the members 8, 12 and 14. I do not however, restrict my claims to that construction, since it is obvious that other means than the strap-members 8 and 12 may be used to connect the visor-shape reflector with the lamp-body; such for example, as the construction shown diagrammatically in Fig. 5, in which 1 is 90 the lamp body; 2 is the stationary reflector in the lamp body; 4 is the cap-ring; 5 the glass front of the lamp; 6 the visor-shape detachable reflector having a corrugated member 7 conformed to the outer surface of the 95 part of the clamping ring with which it is in contact, but not having the strap-members 8 and 12; and a screw 20 or equivalent connecting device, adapted to connect the reflector 6 and the ring 4 with the lamp-body 100 1, so that upon withdrawing the connecting device, the reflector 6 may be detached, and

the connecting device 20 may be restored to securely connect the ring 4 with the lamp-body.

Referring to Fig. 2, it will be noted that 5 the upper central part of the reflector 6, shown in section, is inclined at an angle of approximately 60 degrees relative to the vertical plane of the front of the lamp, and projects outwardly from the front of the 10 lamp a distance somewhat greater than the diameter of the front of the lamp. This form of the reflector 6 is of the essence of my invention, and is of especial value because the entire reflecting surface of the 15 concave stationary reflector 2 is within the field of the reflecting surface of the vizor-shape reflector 6; hence all the rays of light projected against the reflector 2 will go to the reflector 6 and it will project all the 20 rays downward, so that practically all the light will be applied on the roadway below the reflector 6, as indicated by darts in Fig. 2. I am aware that hemispherical concavo-convex guards have been used to tempor- 25 rarily close somewhat more than half the front of the lamp, but such guards are not adapted to utilize all the light, to illuminate the roadway in front of the vehicle. In Fig. 6 I have shown diagrammatically, a 30 permanent concavo-convex reflector 2; a light 3; a hemispherical concavo-convex shield 21 and a vizor-shape concavo-convex reflector 6, and have indicated by darts the direction of reflected rays 30 and 31. Here 35 it is to be noted that if the shield 21 alone be used in connection with the reflector 2, the reflected rays 30 and 31 will be projected forwardly and upwardly beyond the field of the shield 21 and into the atmosphere in 40 front of the shield and might dazzle a person in front of and close to the lamp. If the vizor-shape reflector 6 alone be used in connection with the reflector 2, it will be noted that the same rays 30 and 31 will be 45 projected upwardly and forwardly within the field of the reflector 6 and will be reflected forwardly and downwardly upon the road. In the first instance the light would be projected upwardly and forwardly in 50 a manner tending to confuse the driver and tending to confuse a pedestrian in front of the lamp; in the second instance the light will be cast upon the road where it will be a safe guide for the driver and cannot dazzle 55 a person in front of the lamp.

In practice I have found that when the supplemental reflector 6 is used in conjunction with the permanent reflector 2, the illumination of the road in front of the 60 lamp is much better than it is when the permanent reflector alone is used; and I attribute this superior illumination to commingling with the direct rays normally going to the ground a large number of rays re-

flected by the supplemental reflector, which 65 in the absence of the supplemental reflector would be diffused in the atmosphere.

The constructions hereinbefore described are effective for proper control of the light of most of the lamps now in use; there are 70 however, some lamps in which the bulb is movable forwardly and rearwardly along its horizontal axis for the purpose of properly focusing the light in the permanent reflector 2. I have found in practice that in 75 some lamps of this type, if the bulb be moved forwardly the light rays may in some cases be projected forwardly outside the scope of the body of the supplementary reflector and may produce a confusing glare 80 in front of the lamp. I have also found in practice that if a reflector body 6 having a circumferential corrugation 7 and strap members 8 and 12 conformed to the circumference of a lamp body of given diameter be 85 expanded on a lamp body of considerably greater circumference, the expanding of the members 7, 8 and 12 may result in raising the supplemental reflector body to such extent that some rays reflected from the lower 90 half of the permanent reflector may be projected forwardly under the lower edge of the supplemental reflector body and may cause objectionable glare. To overcome these objections I provide an adjustable ext- 95 ension 32 of light and flexible sheet metal, conformed to the outer surface of the vizor-shape reflector 6; and I also provide slots 33 in the wall of the reflector 6 to accom- 100 modate bolts 34 which extend through suitably placed holes 35 in the extension and through the slots 33 and serve to adjustably connect the extension 32 with the reflector 6, so that upon loosening the bolts the exten- 105 sion may be slid downwardly and forwardly upon the reflector to lengthen it and increase its scope so that it will take all the rays reflected by the permanent reflector.

Having fully described my invention, what I claim as new and desire to secure by Let- 110 ters Patent is:

1. In an appliance of the class described, the combination of a lamp body equipped with a permanent reflector; a supplemental reflector in coöperative relation to the permanent reflector of the lamp body; and an extension adjustable on the supplemental reflector, to vary the scope of the supplemental reflector. 115

2. A reflector comprising a slotted reflector body; a perforated extension conformed to the reflector body, and connecting devices extending through the perforations of the extension and through the slots in the reflector body to adjustably connect the extension with the reflector body. 120

3. In an appliance of the class described, the combination of a permanent reflector 125

body; an inclined vizor-shape reflector connected with the permanent reflector body; an extension complementary to the vizor-shape reflector and adjustable forwardly and 5 rearwardly thereon; and means for securing the extension in different positions on the vizor-shape reflector.

In witness whereof I have hereunto signed my name at Springfield, Illinois, this 18th day of May, 1918.

FRED R. COATS.
